UNITED STATES PATENT OFFICE.

GEORGE H. PALMER, OF LANSING, MICHIGAN, ASSIGNOR TO DAIL STEEL PRODUCTS COMPANY, OF LANSING, MICHIGAN, A CORPORATION OF MICHIGAN.

WAGON.

Application filed November 16, 1921. Serial No. 515,444.

To all whom it may concern:

Be it known that I, GEORGE H. PALMER, a citizen of the United States, residing at Lansing, in the county of Ingham and State 5 of Michigan, have invented certain new and useful Improvements in Wagons, of which the following is a specification.

This invention relates to wagons and more particularly to that class known as express 10 or toy wagons designed for use by children, although the improvements hereafter described will be found applicable to wagons of other types and size.

The present invention has for its objects 15 among others to provide a simple, strong and durable wagon, formed entirely of metal, preferably steel, the parts composing the same being capable of being readily struck-up from sheet material and given the 20 requisite form, and the parts assembled with ease and rapidity, and not requiring skilled labor. Furthermore, the parts are readily replaceable in case of necessity, but are not liable to injury or breakage from ordinary 25 causes.

Other objects and advantages of the invention will hereinafter appear and the novel features thereof will be particularly pointed out in the appended claims.

30 The invention, in its preferred form, is clearly illustrated in the accompanying drawings, which, with the numerals of reference marked thereon, form a part of this specification, and in which—

35 Figure 1 is a side elevation, with the tongue broken off.

Figure 2 is a side elevation of the body with the other parts shown as in substantially central vertical longitudinal section.

40 Figure 3 is a bottom plan with the wheels removed and the ends of the axles and other parts broken away.

Figure 4 is an enlarged vertical section on the line 4—4 of Figure 5, looking in the direction of the arrows.

45 Figure 5 is a vertical section on the line 5—5 of Figure 4, looking in the direction of the arrows.

Like numerals of reference indicate like 50 parts throughout the different views.

Referring to the drawings,

1 designates the body, the bottom 2 and sides 3 of which are stamped up from a single piece of sheet material, preferably 55 steel, the ends 4 being formed separately

and provided with flanges 5 which embrace the ends of the bottom and the ends of the sides, being secured by rivets or the like 6, as seen best in Figures 1 and 2. 7 is a marginal edge protector supported upon the 60 upper edge of the ends and sides and affixed in position thereon in any suitable manner, the same being of any desired width. This constitutes a cheap, yet strong and durable 65 and neat appearing body.

Upon the under side the body is strengthened by transverse members 8, in the present instance shown as two in number, arranged upon opposite sides of the transverse center 70 of the bottom, although the number and the relative disposition thereof may be varied at will. Each of these members, in the present instance, is shown as having a central rib portion 9 formed by bending the material at a point midway its edges, leaving the flanges 75 10 and 11, as seen best in Figure 3, which flanges are riveted or otherwise secured to the under side of the bottom 2 by any suitable means, as seen at 12 in Figure 3.

Near opposite ends of the body upon the 80 under side thereof there are secured by suitable means as rivets 13, see Figure 4, the inverted channel irons 15, see Figures 1, 2 and 4.

16, see Figure 4, is the upper bolster, 85 formed of channel iron, the end flanges 17 of which embrace the side walls of the member 15, the two parts being secured together by bolts 18 and nuts 19 or other suitable means. The upper front bolster is rigidly 90 braced by means of braces 20, see Figures 1, 2 and 3, which are suitably secured to the side wall of the upper bolster, as seen at 21, their other ends being securely bolted or otherwise affixed to the flange 10 of the 95 transverse brace member 8 and to the bottom of the body.

The front lower bolster 22 is of substantially the same formation as the upper bolster, being of channel iron and its lower 100 flanged ends 23 embrace the front axle 24 and are secured thereto by means of the bolts or the like 25, as seen best in Figure 4. The front axle is mounted to turn on the bolt 26 passed downward through the bottom 2 of the body and the transverse channel member 15 and through the upper bolster 16 and through the lower bolster 22 and through the cup-shaped member 27 which is disposed within the channel of the lower 110

bolster and secured thereto in any suitable manner, as by welding, brazing or the like. The lower end of the bolt 26 is supported in a channel iron brace member 28, as seen in Figures 4 and 5, as well as in Figures 1, 2 and 3, the other end of said brace member 28 which, as seen in Figures 1 and 2, is of angular form, being bolted or otherwise secured to the flange 10 of the forward transverse brace member 8 and the bottom 2 of the body.

Secured at their rear ends, as at 30, see Figure 3, to the front axle 24 are the inclined twisted braces 31 having their forward ends arranged parallel and spaced apart, as seen at 32 in Figure 3, and between these spaced apart parallel portions 32 is disposed the forward end of the central longitudinal brace member 33, the rear end 20 of which is sleeved upon the bolt 26, as will be readily understood upon reference to Figure 2.

34 is a clip member, the horizontal portion of which bridges the two parallel portions 32 of the braces 31 and is secured to the end portion 35 of the brace 33 by a rivet or the like 36, as seen in Figure 5. The side portions 37 of this clip embrace the said portions 32 of the braces 31 to which they 30 are secured by suitable rivets or the like 38.

38' is the tongue, of angle iron, pivotally mounted on a suitable pivot 39 which is supported in the members 37, as shown, the tongue or handle 38' having its rear end extended beyond its pivot and adapted to engage the under side of the member 34, as seen in Figure 5, so as to limit the downward movement of the forward end of the tongue or handle, as will be readily understood upon reference to said Figure 5.

40 is the upper portion of the rear bolster, being formed of angle iron and substantially the same shape as the upper portion 16 of the front bolster. 41 is the lower portion of the rear bolster, being substantially the same as the lower portion 22 of the front bolster, being formed of channel iron and having end flanges, as at 42, which embrace the rear axle 43, while 44 are forwardly and 50 upwardly inclined brace arms which are secured to the rear axle by suitable means, as rivets or the like 45, as seen in Figure 3, the forward ends of these members 44 being secured to the flange 10 of the rear transverse brace member 8 and the bottom 2 of the wagon by bolts or the like 46, see Figures 1, 2 and 3. The end flanges 47 of the upper portion 40 of the rear bolster embrace the flanges of the rear transverse member 15, as 55 seen in Figures 1 and 2, and suitable bolts or the like 48 are employed for fastening the interengaged flanges of the members 40 and 15 together and to the bottom of the wagon.

As will be seen clearly in Figure 2, the 65 upper and lower rear bolster portions 40

and 41 are inversely arranged so that their horizontal portions are in contact with each other and they are thus secured by suitable means, as rivets 49, as seen in Figure 2.

The wheels 50 may be of any well-known 70 or approved form of construction, preferably solid disc wheels, that is wheels without spokes, and having suitable rubber tires or the like 51.

It will be evident that an all-metal, preferably steel, wagon constructed as above will possess the greatest strength with minimum weight and one that will be exceedingly durable, neat in appearance and capable of 80 withstanding the rough usage to which a wagon of this character is liable to be subjected.

Modifications in detail, proportion of parts, etc., may be resorted to without departing from the spirit of the invention or 85 sacrificing any of its advantages. The angle iron members are preferably, although not necessarily, of pressed steel, and it is to be noted that the construction shown and described permits the interchanging of parts 90 in the front and rear bolsters.

What is claimed as new is:—

1. An all-metal wagon body having transverse braces upon its under side, formed of angle iron, and upper bolsters of angle iron 95 inversely arranged with the flanges thereof and of the braces interengaging.

2. In a wagon of the character described, a body, a transverse brace on the under side thereof formed of angle iron, an upper bolster portion of angle iron arranged with its flanges interengaged with those of the brace, and a lower bolster section of angle iron the flanges of which are adapted to embrace the ends of an axle. 100

3. In a wagon of the character described, a body, a transverse brace on the under side thereof formed of angle iron, an upper bolster portion of angle iron arranged with its flanges interengaged with those of the brace, a lower bolster section of angle iron the flanges of which are adapted to embrace the ends of an axle, and inclined braces secured to the under side of the body and adapted to engage said axle. 110

4. In a wagon of the character described, a body, an angle iron transverse brace on the under side thereof, a bolster comprising upper and lower portions of angle iron 120 reversely arranged, the side flanges of the upper portion interengaged with the side flanges of said brace and the lower portion having its flanges arranged to embrace an axle.

5. In a wagon of the character described, a body, an angle iron transverse brace on the under side thereof, a bolster comprising upper and lower portions of angle iron 125 reversely arranged, the side flanges of the upper portion interengaged with the side 130

flanges of said brace and the lower portion having its flanges arranged to embrace an axle, and inclined braces secured to the under side of the body and to the rear axle and 5 engaging the flanges of the lower portion of the bolster.

6. In a wagon of the character described, a bolster of pressed out channel construction formed of inversely arranged portions of 10 angle iron, an axle received in the flanges of the lower portion of the bolster, a transverse brace interengaging with the angles of the upper portion of the bolster, and means securing said brace and upper portion of the 15 bolster to the wagon body.

7. In a wagon of the character described, a body, a bolster of upper and lower angle iron portions reversely arranged, an axle

retained in the flanges of the lower portion of the bolster, and a tongue support formed 20 of members secured to the axle, and a member secured to said members and sleeved upon the king bolt.

8. In a wagon of the character described, a body, a bolster of upper and lower angle 25 iron portions reversely arranged, an axle retained in the flanges of the upper portion of the bolster, a tongue support formed of members secured to the axle, a member secured to said members and sleeved upon the 30 king bolt, and a clip secured to the ends of said tongue support members and adapted to receive the supporting pivot for the tongue.

In testimony whereof I affix my signature. 35
GEORGE H. PALMER.
